UNITED STATES PATENT OFFICE

2,429,109

STRUCTURAL TOY ASSEMBLY MEANS

Earl M. Roach, Chicago, Ill., assignor to Arvey Corporation, Chicago, Ill., a corporation of Illinois

Application July 12, 1944, Serial No. 544,540

2 Claims. (Cl. 29—286)

1

This invention relates to the construction of toys such as model airplanes and the like, and particularly to a novel means for aiding or facilitating the assembly of such structural toy parts.

The provision of toy airplane kits in the form of structural parts simulating various models of airplanes for the amusement and education of children is well known. Such kits conventionally comprise various frame former elements such as body formers, wing ribs, stringers, struts, and the like parts which require assembly by proper positioning and alignments of the respective parts, followed by gluing them together. For such purpose various assembly aids have been provided.

It is an object of the present invention to provide new and improved assembly aid, particularly adapted for the construction of toy airplanes, which is of simple construction, easy to set up and assemble and which not only greatly facilitates the construction process, but additionally reduces the degree of skill required in making the assembly and at the same time is conducive to more accurate and better results.

In general the present invention relates to means for aiding in the assembly of and for positioning and supporting toy airplane frame former elements such as body formers, wing ribs and the like structural parts, which includes one or more frame former element alignment rails, each rail comprising an elongated strip of sheet material formed with a series of spaced slots of limited depth opening to one longitudinal edge thereof, and a series of frame former elements of sheet material adapted to be transversely received and positioned in the slots of the rail or rails to be held in spaced parallel alignment thereby.

The frame former elements are each formed with a slot of limited depth opening to a peripheral edge portion, or when more than one rail is employed, the former elements are provided with an equivalent number of angularly spaced slots, for embracing engagement with the rail or rails beneath the slots thereof to prevent lateral displacement of the frame or body former elements by reason of the slotted interlock engagement of the rail or rails and former elements with each other.

Further objects relate to other details of construction and arrangement of parts and the advantages and economies thereof which will be apparent from a consideration of the following specification and drawings wherein:

Fig. 1 is a side elevation of one form of my invention employing a single alignment rail for the assembly of the fuselage of a toy airplane, with

2

body formers positioned therein in slotted interlocked engagement.

Fig. 2 is a plan view of the form of my invention illustrated in Fig. 1.

5 Fig. 3 is a section on the line 3—3 of Fig. 1.

Fig. 4 is a fragmentary perspective detail of one end of the alignment rail illustrated in Figs. 1 and 2.

10 Fig. 5 is an elevation of a slotted body former element adapted for interlocking engagement with the alignment rail in the preceding figures.

Fig. 6 is a perspective view of a single alignment rail of modified form of construction.

15 Fig. 7 is a fragmentary perspective detail of one of the alignment rails illustrated in Fig. 6.

Fig. 8 is a fragmentary perspective detail view of an alignment rail similar to that of Fig. 6 and a slotted wing rib adapted for interlocking engagement therewith.

20 Fig. 9 is a side elevation of another modified form of assembly means illustrating the employment of three alignment rails with body formers in slotted interlocked engagement therewith.

Fig. 10 is a plan view of the arrangement illustrated in Fig. 9.

25 Fig. 11 is an end elevation viewed in the direction of the line 11—11 of Fig. 9.

Fig. 12 is a section on the line 12—12 of Fig. 9.

30 Fig. 13 is an elevation of a slotted body former adapted for interlocking engagement with the three rails illustrated in the construction of Fig. 9.

Fig. 14 is an elevation of a slotted end stabilizer plate employed in the arrangement of Fig. 9.

35 Fig. 15 is a plan view of a further modified form of construction employing three alignment rails.

Referring to the drawings, particularly Figs. 1 to 5, the reference numeral 10 indicates an alignment rail in accordance with my invention

40 adapted for the assembly of a fuselage of a toy airplane, and comprises an elongated strip of sheet material such as cardboard, provided with a plurality of longitudinally spaced slots 11 of limited depth and width opening to the upper longitudinal edge thereof. In this form, the slots 11 may be of equal depth and of a width sufficient to frictionally engage body formers 12.

45 For the purpose of providing the proper longitudinal contour of the fuselage, and to position a series of body formers 12, which may be of varying contour and diameter, the upward defining or longitudinal edge of the strip 10 may be angularly or arcuately contoured as illustrated to suit the particular model of airplane being simulated.

For the purpose of securing the alignment rail 10 to a suitable mounting surface while the model airplane is being assembled and constructed, the lower longitudinal edge of rail 10 is provided with laterally extendible flange 13, by means of which the rail may be tacked to a suitable table or base board. The opposed ends of the flange 13 are provided with contiguous upwardly foldable flaps 14 adapted to frictionally lock against the notched cut out end 15 of the alignment rail. This tab 14 is adapted to be folded upwardly so as to extend perpendicularly to the flange 13 and transversely of the body of the rail 10 so as to permit the rail 10 to be maintained in edgewise elevated position with its slots 11 opening upwardly.

The frame or body formers 12 in addition to being provided with the conventional peripheral notches 16 for lodgement of the conventional stringers 17, is provided with an additional relatively elongated notch or slot 18 of limited depth and a width substantially equal to the thickness of the material of which the alignment rail 10 is composed. It will be understood as previously indicated that the body formers 12 are provided in a series, each adapted to be engaged in a respective notch 11 of the rail 10, and in accordance with my invention the body formers 12 are adapted to be transversely received in the slots 11 of the rail 10 in a manner whereby the frame or body former elements 12 descend to the limit of the depth of the slot 18 within the slots 11 of the rail 10 and to the limits of the depth of slots 11 whereby these two components at their respective slotted areas are brought into slotted embracing engagement with each other. This not only holds the two component portions in frictional engagement but by reason of the slotted interlock, the body formers are held against lateral displacement so as to insure alignment of the body formers not only in a longitudinal but in a transverse direction in a predetermined manner as to thereby reduce the skill or care necessary in assembly, and to thereby facilitate construction and insure a more accurate and pleasing result.

After the body formers 12 have been positioned in alignment by means of the rail 10, stringers 17 may be longitudinally engaged to the body formers 12 by seating them and gluing them within the notches 16. After the stringers 17 have been glued to a major portion of the periphery of the fuselage defined by the contour of the body formers 12, and the glue dried, the fuselage composed of body formers 12 and assembled stringers 17 may be removed as a unit from the rail 10 and the necessary remaining stringer or stringers attached, and for this purpose the opening of the notch 18 may be employed for engagement of a stringer in a manner similar to the employment of the notches 16.

The form of construction illustrated in Figs. 6 and 7 comprises a single alignment rail 19 formed of an elongated strip of sheet material of cardboard or the like, the lower edge thereof being provided with a laterally extendible flange 20 by means of which the rail may be engaged to a suitable support by means of a thumb tack or otherwise. The alignment rail 19 is caused to be edgewise elevated by means of a pair of transverse stabilizer strips 21 each provided with a downwardly opening slot 22 adapted for interlocking engagement through the upwardly opening slots 23 adjacent the ends of the rail 19, the joint depths of the slots 22 and 23 permitting

the strip 21 to descend so that the lower marginal edge of the strip 21 may be brought into parallel abutting engagement with the surface of the support on which the rail 19 is to rest.

The alignment rail 19 is provided with a series of upwardly opening slots 24 of a width adapted to frictionally engage the body formers 12, and the slots are limited a predetermined depth although in this instance since the upper longitudinal edge of the rail 19 is parallel to the lower longitudinal edge thereof, the slots 24 are of limited but of varying depth, the depth of the slots 24 being predetermined by the contour of the model airplane to be simulated and the relative size, contour or diameter of the body formers 12.

As described with respect to the form of construction of Figs. 1 to 4, the body formers 12 are adapted to be seated within the slots 24 of the rail 19 and to be brought into slotted interlocking engagement therewith, to likewise seat, align, and maintain the body formers 12 not only in desired spaced, parallel, longitudinal alignment, but in predetermined symmetrical position and guarded against accidental rotative or lateral displacement.

Fig. 8 illustrates the employment of an alignment rail 5, which is generally similar to rails 10 or 19, and is similarly provided with a series of upwardly opening slots 6 for reception of and for slotted interlocking engagement with a wing rib element 7. This rib, similar to the body formers 12, is provided in a series, each formed with a slot 8 opening to one edge, so that when the rib 7 is positioned with a designated slot 6 and urged down to the depth of its slot 8, the rib is held not only in frictional engagement but held in predetermined position both longitudinally and transversely of rail 5 and locked against accidental lateral displacement, in the manner and for the purpose set forth with respect to the body formers. It will therefore be understood that my described construction is applicable in like manner to the frame formers of the class described in general including body formers, wing ribs, stabilizer ribs, and the like.

Figs. 9 to 13 illustrate a modified and preferred form of toy airplane frame former alignment means wherein a plurality of, and specifically three, alignment rails are jointly employed for the purpose of insuring both longitudinal and lateral alignment of frame formers by means of cooperative slotted interlocked engagement of the frame formers with the alignment rails.

Referring specifically to Figs. 9 to 14, I employ a group of three alignment rails indicated as 28, 28 and 28', each being in the form of an elongated strip formed of cardboard sheet material and each being provided with a series of slots 29 of limited depth and width opening to one longitudinal edge and adapted for reception and engagement of the body formers 30, these slots 29 being formed in a series of predetermined depth adapted for reception or alignment of the body formers 30. The rails 28' of the group may be provided with a flange 31 extendible laterally from the longitudinal edge thereof opposed to the one from which slots 29 open, whereby it may be engaged by means of suitable thumb tacks or the like to a suitable mounting or supporting surface.

For the purpose of laterally stabilizing rail 28' and to maintain it in edgewise elevated position, I provide a pair of end plates 32' which may be of a peripheral contour substantially similar to the frame or body formers 30, and where feasible

may actually be employed as body formers. These end plates, however, are provided with a flattened peripheral portion indicated as 33 and a group of three slots 34, 34 and 34', opening to the periphery thereof, slot 34' opening to the flattened portion 33, these slots being adapted for the reception of the rails 28, 28 and 28' respectively, the rails being provided also with companion slots adjacent their ends for slotted interlocking engagement. It will be understood that with lesser effect, I may dispense with the stabilizers 32 in this form of plural alignment rail arrangement, or I may obtain stabilization through employment of means such as the tabs 14 of Figs. 1 to 4 or the stabilizer strip 21 of Figs. 6 and 7, in association or engagement with rail 28', although not illustrated.

When employing such group of three alignment rails, the body formers 30 are likewise provided with a group of three angularly spaced slots 35 of limited depth opening to the outer periphery, the width of the slots being substantially equal to the thickness of the rails 28 and 28'. These body formers 30 similar to the body formers 12 described with respect to the previous form of construction are similarly provided with notches 36 for the positioning and engagement of stringers, and they may likewise be provided in suitable contour and varying size in a series to conform to the fuselage contour of the model of the airplane being simulated as previously described.

In aligning the body formers 30 preparatory to securing the stringers thereto the two end plates 32 are engaged with the rail 28 adjacent the opposed ends thereof, and thereafter the series of body formers 30 are seated within the respective and pre-designated slots 29 on rail 28', the area defining one of the slots 35 on each of the body formers being urged down into embracing engagement with the rail 28' below the slots 29 thereof so as to bring the two component portions into not only frictional but slotted interlocking engagement. Thereafter the two additional rails 28 are seated in the two additional slots 35 of the body formers and the slots 34 of the end plates 32, and likewise urged into slotted interlocking engagement. In this manner the body formers are firmly and securely maintained against lateral misalignment or displacement in positive parallel alignment with each other, each of the three rails 28, 28 and 28' being in slotted interlocked engagement with each of the series of body formers 30 and the end plates 32.

Thus in view of the firm position and stability of the body formers 30 it will be apparent that suitable stringers, such as conventional stringers 17 illustrated and described with respect to the previous form of construction, may be seated and adhesively engaged within the notches 36 of the body formers 30 between the three alignment rails, with insurance of a high degree of accuracy in construction and assembly. After the adhesive by means of which the stringers have been secured to the body formers has set, the three rails 28, 28 and 28' may be removed and added stringers secured at the outer ends of the openings of slots 35 to complete the fuselage frame assembly.

Fig. 15 illustrates a form of assembly employing a group of three rails 38, 38 and 38', each provided with a series of longitudinally spaced slots 39 opening to one longitudinal edge, these

slots 39 being of a width adapted to receive a body former 30, but in this instance all the slots 39 are of equal depth similar to the rail 10 previously described, in view of the fact that the longitudinal edge of these rails to which the slots open are of angular or curvilinear contour similar to the contour of rail 10 and for like purpose. This form otherwise functions similar to the arrangement of Figs. 9 to 14 with like advantages.

It will be understood with respect to the forms of Figs. 9 to 15 that although a group of three slotted alignment rails are employed with body formers having three slots for cooperative and slotted interlocking engagement therewith, that other plural numbers of alignment rails may be employed such as 2 opposed rails or 4 radially spaced rails, not illustrated, although I prefer to employ three as illustrated and described.

20 I claim as my invention:

1. In a device for aiding in the assembly of and for positioning and supporting toy airplane frame former and the like structural parts of the class described, a plurality of frame former element alignment rails each comprising an elongated strip of sheet material formed with a like series of spaced slots of limited depth opening to one longitudinal edge, and a series of frame former elements of sheet material adapted to be transversely received and positioned in spaced parallel alignment thereby, said frame elements being each formed with a plurality of angularly spaced slots of limited depth opening to the outer defining edge for embracing engagement with said rails beneath the slots thereof whereby to maintain the rails and the frame elements in slotted interlocked engagement with each other.

2. In a device for aiding in the assembly of and for positioning and supporting toy airplane frame former and the like structural parts of the class described, frame former element alignment rails comprising a group of three elongated strips of sheet material each formed with a like series of spaced slots of limited depth opening to one longitudinal edge and series of frame former elements of sheet material adapted to be transversely received and positioned in spaced parallel alignment thereby, said frame elements being each formed with three substantially equiangularly spaced slots of limited depth opening to the outer defining edge for embracing engagement with said rails beneath the slots thereof whereby to maintain the rail and the frame elements in slotted interlocked engagement with each other.

EARL M. ROACH.
